UNITED STATES PATENT OFFICE.

THOMAS MURPHY AND JOHN W. BROADHEAD, OF PROVIDENCE, RHODE ISLAND.

SHUTTLE-MOTION FOR LOOMS.

SPECIFICATION forming part of Letters Patent No. 415,879, dated November 26, 1889.

Application filed March 18, 1889. Serial No. 303,658. (No model.)

To all whom it may concern:

Be it known that we, THOMAS MURPHY and JOHN W. BROADHEAD, both of Providence, in the county of Providence and State 5 of Rhode Island, have jointly invented certain new and useful Improvements in Shuttle-Motions for Looms, of which the following is a full, clear, and exact description, reference being had to the accompanying drawings, 10 forming part of this specification.

The object of our invention is to provide a device which will support the sweep-stick and strap and allow of the same being readily adjusted, so as to exert more or less power 15 through the picker-stick.

To the above purposes our invention consists in the combination of the different parts of the device, as will be more fully set forth hereinafter.

20 In the accompanying drawings, Figure 1 represents a side view of our improved device in operative position. Fig. 2 is a perpendicular sectional view showing the sweep-stick and part of the sweep-strap and pad in section and a portion of the picker-stick. Fig. 25 3 is a sectional view taken on the line 3 3 of Fig. 1. Fig. 4 is a sectional view taken on the line 4 4 of Fig. 1, and Fig. 5 is a perpendicular sectional view showing another form 30 of sweep-strap.

In the drawings similar numbers of reference designate corresponding parts throughout.

Referring to the drawings, 6 indicates an 35 arm, which is supported on the lay-shaft 7; 8, the picker-stick, which is mounted on the arm 6.

9 is the sweep-stick, and 10 the sweep-strap. 40 11 is a light rod, preferably made of metal. 45 12 designates an adjustable slide secured on the arm 6 and having the slot 13 and boss 14. The bolt 15 is provided with the shoulder 16 and extension 17, upon which the picker-stick 8 is pivoted and held in place by the pin 18. The bolt 19, passing through the 50 sweep-strap and sweep-stick, is provided with a shoulder 20 and an extension 21.

The object of the slot 13, formed in the slide 12, is to allow of the slide being moved 55 on the bolt 15 to lift or lower the sweep-strap and sweep-stick through the rod 11, and, as it

is desirable that the rod 11 should maintain a position parallel to the picker-stick, the end of the slide carrying the boss 14 would necessarily be lifted or lowered as well as 55 moved toward or away from the bolt 15, whereby the slide 12 would assume a diagonal position. The bolt 15 is passed through the slot 13 in the slide 12, then through a hole in the arm 6, when the nut 22 is screwed up, 60 so as to securely hold the slide in the desired position and yet allow of a free movement of the picker-stick 8 upon the extension 17. The rod 11 is pivoted at one end on the extension 21 and at the other end on the boss 65 14, on both of which it is held by the pins 23 and 24, respectively, so as to freely move with the picker-stick. It will be readily seen that by loosening the nut 22 the slide can be adjusted so that the rod 11 may be lifted or 70 lowered, and with it the sweep-stick and sweep-strap, and at the same time the lower end of the rod 11, supported on the boss 14, may be moved in or out from the middle line of the picker-stick to correspond to the position of the upper end, supported on the extension 21, after which, the nut 22 being screwed up, the bolt 15 will securely hold the slide in the desired position, and the rod, 75 being pivoted on the boss 14, will maintain a 80 position parallel with the picker-stick.

By reason of supporting the sweep-stick by the rod 11 we are enabled to use a metallic sweep-strap, if preferred, in which case we use a pad 25, which is formed with angular 85 faces, so as to give a better bearing on the picker-stick.

In Fig. 5 we have shown the strap 10 as formed with angular faces, a flat strap being used for the pad, but producing the same result as that shown in Fig. 2.

All the parts are simple and durable in construction and allow of the ready adjustment of the sweep-strap on the picker-stick, so that more or less force may be brought to 95 bear by the same on the shuttle.

Having thus described our invention, we claim as new and desire to secure by Letters Patent—

1. The combination, with a picker-stick, the 100 sweep-stick, and sweep-strap of a loom, of a supporting-rod pivotally secured to an ad-

justable slide and to the sweep-stick and the adjustable slide adjustably secured by the fulcrum-pin of the picker-stick, substantially as herein shown and described.

5 2. The combination of the sweep-strap provided with a pad, the sweep-stick, the supporting-rod, the adjustable slide, and the picker-stick, substantially as herein shown and described.

10 3. The combination of the picker-stick 8, adjustable slide 12, rod 11, the sweep-stick 9, and sweep-strap 10, substantially as herein shown and described.

15 4. The combination of the picker-stick 8, adjustable slide 12, provided with the slot 13 and boss 14, the bolt 15, provided with the

collar 16, the nut 22, the sweep-stick 9, the sweep-strap 10, and the rod 11, mounted on the boss 14, for supporting the sweep-strap 10 and sweep-stick, substantially as herein shown and described.

5. The combination of the picker-stick 8, adjustable slide 12, provided with the boss 14, the bolt 19, and the rod 11, the sweep-stick 9, and sweep-strap 10, provided with 25 the pad 25, substantially as herein shown and described.

THOMAS MURPHY.
JOHN W. BROADHEAD.
